UNITED STATES PATENT OFFICE.

CHARLES M. STARR, OF SOUTH BEND, INDIANA.

TIRE-PUMP.

1,346,919.

Specification of Letters Patent. Patented July 20, 1920.

Application filed May 10, 1919. Serial No. 296,172.

To all whom it may concern:

Be it known that I, CHARLES M. STARR, a citizen of the United States, residing at South Bend, in the county of St. Joseph 5 and State of Indiana, have invented certain new and useful Improvements in Tire-Pumps, of which the following is a specification.

The invention relates to tire inflating pumps, and more particularly to air pumps 10 of the type adapted for ready attachment to some means of support for holding the same firm during the manipulation thereof.

The object of my invention resides primarily in the provision of means in connection with a tire inflating pump for automobiles, whereby the pump may be clamped for its support to the running board of the automobile with a minimum amount of effort and expenditure of time. A further object resides in providing pumps of said type with means for clamping same to the running board by the single operation of a lever, whereby the same may be quickly attached to or detached from the running board, and a material saving of time effected in said operations as compared with screw operated means adapted for the same purpose. Another object resides in the provision 20 of a pump operating lever, and a clamping lever, and a removable handle adapted for operating either lever. A still further object is to provide the clamping means with an adjustable head, whereby, when once adjusted with relation to a particular running board in order to obtain the desired clamping effect, no further adjustment will be required.

With the above and other objects in view, 40 the invention in the preferred form of details will be described in the following specification, reference being had particularly to the accompanying drawings, in which:

Figure 1 is a side elevation of an air pump 45 embodying the improvements.

Fig. 2 is a similar view seen from another direction, the running board of an automobile being shown in section.

Fig. 3 is a section of the clamping means 50 taken on the line 3—3 of Fig. 2.

The pump illustrated in the drawings is of a conventional type, and the particular type of pump employed is immaterial, in so far as the present invention is concerned.

55 As shown, the pump comprises a cylinder 5,

a piston 6, the piston rod 7 of which is pivotally connected with an operating lever 8, having a stub arm 9, adapted to fit the socketed end 10 of a detachable handle 11. The arm 12 of the lever is formed with a 60 cross-arm 13, the ends of which have pivotal connection at 14 with the upper ends of swinging rods 15, the lower ends of which are pivotally supported at 16 upon the pump base 17, the function of the parts recited 65 and the mode of operation of the pump being well understood in the art.

Preferably formed integral with the pump base 17, and depending from the marginal edge thereof, are spaced elongated 70 bearing lugs 18, and a single upwardly extending bearing lug 19 in vertical alinement with a center line drawn between the lugs 18. Pivotled between the lugs 18, as at 20, is an angle lever 21, one arm of which lever 75 extends beneath the pump base and carries a screw bolt 22 threaded therein. Adapted to rest upon said bolt 22, is what may be termed a bearing head 23, tapered at its end 24 to fit between the spaced lugs 18, and its opposite end provided with a fixed depending pin 25 extending through an aperture in the lever, a coil spring 26 encircling the pin beyond the lever, and tensioned so as to yieldingly hold the bearing head 23 seated 80 upon the bolt 22. The bearing head 23 is preferably of curved formation lengthwise thereof, so as to afford an effective holding contact with the under side of automobile running boards, as indicated at 27, 85 which are provided with a widened edge, as at 28. Such widened edge, as well as the relatively thinner portion of the running board, may thus be both effectively engaged for clamping purposes, while at the same time the bearing head will be adapted 90 for effectively engaging a running board of uniform thickness. Such adaptability is rendered possible because the bearing head is permitted to rock upon its supporting bolt 100 22, and by means of which bolt the bearing head may also be adjusted with relation to the lever which indirectly supports the same, so that, within limits, the clamping means may be adjusted for effectively engaging 105 running boards of varying thickness and cross sectional formation.

The end of the lever 21, through which power is applied in the clamping operation, extends upwardly beside the pump cylinder 110

as shown, and has connection through a toggle, formed by the links 30 and link 31, with the upper end of the lug 19, which interconnection of parts is effected through 5 pivot members 32. The toggle link 31 is provided with an integrally formed stub handle portion 33, formed to fit the socketed end of the handle 11, which latter thus serves for either operating the pump or the 10 clamping means. As shown in Fig. 2 in full lines, when the pivot connecting the toggle links is slightly over center in the clamping operation, the parts will be effectively locked against self retraction.

15 While the foregoing is the preferred form of my invention, I desire it to be understood that I do not limit myself to the precise structure shown and described, as it is obvious that the same may be variously modified without departing from the spirit of the invention.

What is claimed is:—

1. A clamping means comprising a support, clamping means operative to and from the under side of the support including an angle lever, one arm of said lever extending beneath the support and the other extending upwardly with respect thereto, a toggle operatively connected with the upper end of 25 the lever, and means for operating the toggle.

2. A clamping means comprising a support, clamping means operative to and from the under side of the support including an angle lever, one arm of said lever extending beneath the support, and the other extending 35 upwardly with respect thereto, a toggle operatively connected with the upper end of the lever, and a handle carried by one of the 40 toggle links for operating the toggle.

3. A clamping means including a support, an angle lever mounted thereon and in part extending beneath the support, a screw bolt carried by the lever, an elongated bearing head adjustably supported for rocking 45 movement by the bolt beneath said support, and means for preventing relative lateral displacement between the bearing head and the lever.

4. A clamping means including a support, 50 a clamping lever mounted on the support and in part extending beneath the same, an elongated curved bearing head carried by the lever, and means for vertically adjusting the bearing head with relation to the lever 55 and to permit a tilting movement thereof.

5. A clamping means including a support, spaced bearing lugs depending from the support, a clamping lever pivotally supported between said lugs, a bearing head having 60 one end thereof extending between said spaced lugs, and its opposite end carrying a depending pin freely extending through an aperture in said lever, and means on the lever for supporting the bearing head in vertical 65 and angular relation thereto.

6. A clamping means including a support, spaced bearing lugs depending from the support, a clamping lever pivotally supported between said lugs, a bearing head having one 70 end thereof freely extending between said lugs, and its opposite end carrying a depending pin freely passing through an aperture in said lever, means on the lever for supporting the bearing head in vertical and 75 angular relation thereto, a toggle having connection with the operative end of said lever, and means for operating the toggle.

In testimony whereof I affix my signature.
CHARLES M. STARR.
